UNITED STATES PATENT OFFICE

WILLIAM MAYO VENABLE, OF PITTSBURGH, PENNSYLVANIA, ASSIGNOR TO BLAW-KNOX COMPANY, OF PITTSBURGH, PENNSYLVANIA, A CORPORATION OF NEW JERSEY

BUCKET CONSTRUCTION

Application filed December 21, 1928. Serial No. 327,635.

This invention relates to excavating buckets of the type sometimes referred to as "clam shell" buckets.

The principal object of the invention is to 5 simplify and improve the construction of buckets of this character so that parts which wear may be more readily renewed, and so that certain parts of the same size can be utilized for buckets of different sizes with 10 but a minimum of trouble and expense in adapting such parts to the specific size desired.

Another object of the invention is to adapt 15 the construction or framework of the bucket to scoops of very many different sizes and shapes by means of which the bucket can be easily adapted to handle a wide variety of materials under the many diverse conditions met with in service.

Another object of the invention is to secure 20 great strength with minimum weight and to adapt the scoop design in each instance specifically to the materials which are to be handled, in connection with which object I also aim to provide as strong a connection 25 between the hinge members and the corner brackets of the scoop as may be desirable without resorting to the use of heavy plate in the sides of the scoops proper.

More specifically stated, it is the object 30 of my invention to provide a separately formed attaching or connecting member by means of which the hinges, the scoops and the corner brackets are securely united together.

The foregoing, together with such other objects as may hereinafter appear, or are incident to my invention, I obtain by means 35 of a construction which is illustrated in preferred form in the accompanying drawings, wherein—

Fig. 1 is a side elevation of an excavating bucket embodying my improvements.

Fig. 2 is an end view of the lower part of 40 the bucket shown in Fig. 1, and

Figs. 3 and 4 are detailed views illustrating the attaching or connecting means mentioned above.

The bucket illustrated happens to be of the lever arm type and is provided with the

hinge pin 1 upon which is mounted the lever arm plates 2 similar to those which are illustrated, described and claimed in the patent to Robin and Venable, No. 1,686,176.

At each end of the bucket there are a pair 55 of hinge members 3 and 4 which, in this instance, terminate short of the scoop members 5, as will be clearly apparent upon inspection of the drawings, particularly Fig. 1.

The hinge members 3 and 4 are securely 60 and permanently fastened to the intermediate members 6, either by welding or by riveting, as may be preferred. In Fig. 1 I have shown this connection as having been made by the rivets 8a.

The members 6 are made of such thickness, width and shape as to form the upper portion of the scoop or bowl of the bucket and are adapted to withstand all stresses applied by the operating mechanism by means of 70 which the bucket is opened and closed. Each member 6 has a side web portion 7 which is secured to a hinge member and also a back portion 8 bent at right angles to the web portion 7 with a radius of curvature at the bend 75 or corner 9 suitable for the accommodation of a corner bracket 10. The back portion 8 is in proper alignment to form half of the upper back portion of a scoop. The corner brackets may also be secured by means of 80 rivets 8a or by welding, as may be desired.

I prefer to make the members 6 in pairs, one pair for the top portion of each scoop, the back portions 8 of the two members of each pair being joined together in the middle 85 at the back of the scoop by means of the splice plate 8'. If desired, however, the two members 6 could be made as a single piece without a splice plate.

In the particular type of bucket illustrated 90 the ends of the lever arm plates 2 are secured to the back portions 8 of the members 6 at substantially the middle of the top of the scoop, as clearly shown in Fig. 2, the connection being made either by riveting or welding 95 as may be desired.

It will now be apparent that all of the parts of the bucket, with the exception of the scoops 5 proper, may be assembled first, and that the scoops may be subsequently attached 100

thereto. Furthermore, the scoops 5 may be removed and renewed, or even replaced by scoops or some other design at any time that this may be necessary or desirable.

5 I prefer to rivet the scoops 5 to the members 6 by means of the rivets 8a as shown, but it is obvious that they may be bolted thereto where frequent removals may be necessary, or they may be welded. In any event, however,

10 the scoops are readily removable either by cutting the rivets or the weld seams, or by removing the bolts, without in any way disturbing the connections between the other bucket parts.

15 It should be noted that the member 6 can be made of extremely tough plate, much stronger and tougher in fact than it is possible to use where the member 6 and the hinge member are cast as one piece and the hinge

20 secured directly to the scoop plates. It is a comparatively inexpensive proposition to carry in stock a number of sizes of attaching or adapter members 6, whereas it is rather expensive to cast a plurality of sizes of hinge members and keep on hand a large stock of all sizes.

I claim:—

1. The combination of a bucket hinge member, a scoop, a scoop corner bracket, and a 30 separately formed adapter member to which all of said parts are secured, said hinge member being capable of use with a scoop of a different size by changing the adapter member.

2. The combination of a pair of bucket 35 hinge members, a pair of scoops, and a pair of separately formed adapter members for attaching the scoops to the hinge members, said hinge members being capable of use with scoops of a different size by changing the 40 adapter members.

3. In a bucket, the combination of scoop 45 hinge members, scoop members, and separately formed adapter means connecting the hinge members with said scoop members, said hinge members being capable of use with scoop members of a different size by changing the adapter means.

4. In a bucket, the combination of a pair 50 of scoop members, a hinge pin, hinge members adapted to swing on said pin, scoop corner brackets, and separately formed adapter members for securing a hinge member, a corner bracket and a scoop member together, said hinge members being capable of use 55 with scoop members of a different size by changing the adapter members.

5. As a new article of manufacture, an 60 adapter member for uniting independent scoop and hinge members in an excavating bucket, said adapter member being formed of plate material and having a web portion for overlapping the hinge and the adjacent scoop wall and an angular extension therefrom for paralleling the upper outer wall of the scoop.

65 6. As a new article of manufacture, an

adapter member for uniting independent scoop, corner bracket and hinge members in an excavating bucket, said adapter member being formed of plate material and having a securing web portion for overlapping the hinge and the adjacent scoop wall and an angular extension therefrom for paralleling the upper outer wall of the scoop and providing an embracing corner for said bracket.

70 7. In a bucket, the combination of a hinge pin, a scoop, a hinge casting terminating short of the scoop and mounted on the pin independent of its relation to the scoop, and a separately formed adapter for connecting the hinge casting to the scoop, said hinge casting being capable of use with a scoop of a different size by changing the adapter.

75 In testimony whereof I have hereunto signed my name.
